FIG. 3 is a top view of the power tool, such as a drill, shown in FIG. 1; and,

FIG. 4 is a rear view of the power tool, such as a drill, shown in FIG. 1.

In the present design, the bottom and front of the design are

devoid of surface ornamentation, and accordingly, the bottom

view and front view are omitted.

The broken lines depicting a battery, chuck, and portions of

the design are included for purposes of illustrating unclaimed

features and environmental structure. The broken lines form

no part of the claimed design.

The name Milwaukee displayed in broken lines on the power

tool, such as a drill, is a trademark owned by the Milwaukee

Electric Tool Corporation.
